F. I. GETTY

WELL TOOL

Filed April 21, 1922

UNITED STATES PATENT OFFICE.

FRED I. GETTY, OF JENNINGS, LOUISIANA.

WELL TOOL.

Application filed April 21, 1922. Serial No. 555,895.

To all whom it may concern:

Be it known that I, FRED I. GETTY, a citizen of the United States, residing at Jennings, in the parish of Jefferson Davis and 5 State of Louisiana, have invented certain new and useful Improvements in Well Tools, of which the following is a specification.

This invention relates to well tools, and 10 has as an object the provision of a tool for use in side-tracking. A further object of the invention is the provision of a tool which will cut an opening in the side of the well casing of such a nature that a strainer with 15 liner attached can be lowered therethrough without danger of hanging up on the edges of the opening.

An illustrative embodiment of the invention is shown in the accompanying drawing, in which—

Fig. 1 is a detail vertical section through the lower portion of a well, showing a strainer in place.

Fig. 2 is a like view showing the operation of side-tracking as heretofore practiced.

Fig. 3 is a like view showing the use of a tool embodying the present invention.

Fig. 4 is a side elevation, partly in section, upon a larger scale, showing a tool provided by the present invention, with parts broken out to shorten the figure.

Fig. 5 is a detail side elevation partly broken away of a milling cutter utilized by 35 the present invention.

Fig. 6 is a bottom plan view of the cutter shown in Fig. 5.

Oil wells are usually constructed as shown in Fig. 1, wherein a casing 10 is set in the 40 well after the drilling is completed, the bottom of the well casing being open and a liner 11 having a strainer 12 extending below the well casing is placed within the casing to secure the oil from the oil-bearing sand. The sand about the strainer 12, and the strainer itself, frequently become clogged with paraffin, asphalt or other heavy components of the oil, or through other causes, so as to render the well non-productive.

It has been common practice with such 50 non-productive wells as referred to, to side-track the liner, as shown in Fig. 2 a whipstock 13 having been lowered into place in the well casing. The whipstock, as shown in 55 Fig. 2, tapers to a thin edge 14 at its upper portion, this portion being preferably con-

caved as indicated by the dotted line at 15. The drill stem 16 having a milling cutter 17' at its lower end is then lowered until the cutter is in contact with the whipstock which cams the cutter against the side of the well casing 10 and upon revolution of the drill stem 16 and by feeding it down in the usual way an opening will be made in the side of the well casing 10, as clearly indicated in Fig. 2.

This opening at its best has often given trouble when a strainer is lowered therethrough, since the edges of the opening are too abrupt to avoid danger of hanging up of the strainer when lowered.

The abruptness of the opening is objectionable also, on account of the danger of breaking or twisting off the drill stem, which is more or less bent or curved where it passes through this milled opening, and when rotating under the strain while drilling down to the bottom of the well preparatory to setting the strainer it may break or twist off.

It is objectionable further for the reason that, even though the drilling and setting of the screen and liner may be accomplished successfully, the liner would be too abruptly bent or curved where it passes through the opening and would consequently bend the pump tubing in case the tubing were let down in the liner while the well was being pumped.

To avoid this danger the present invention provides the tool illustrated in Figs. 3 to 6 inclusive, wherein a hollow rod 17 is provided with a plurality of milling cutters 18, 19, 20, 21, four being shown. A greater or less number than that illustrated may be provided upon a single tool.

To permit of the application of the cutters to the rod the rod is formed with a series of offsets growing successively smaller as the lower end is approached. The lower end of each successively different diameter is threaded, the thread preferably being of the nature of a pipe thread, which is tapering, as indicated upon the interior of the cutter at 22 in Fig. 5. Therefore a cutter 21, being applied first, will pass freely over each of the sections 23, 24, 25 and 26 to engage with the thread upon the lower end of the section 27 and each successive cutter will pass freely to its appropriate thread.

Preferably the successive cutters as the lower end of the tool is approached, are

made with thicker walls and wider cutting edges, so that the outside diameter of each is the same. The cutters are provided with milling teeth 28 which project at the periphery of the circle, and also at the bottom edge of the tool, as clearly shown in Fig. 6.

A flattened drill bit 29 is preferably provided upon the end of the tool and the rod 17 is preferably made with a hollow 30 10 having an outlet, or outlets, at 31 in the drill bit whereby water may be passed through the rod to assist in the drilling and milling operation if desired.

The rod 17 is preferably made in two sections, on account of the great convenience in handling and transportation. The rod is therefore screwed together at some intermediate point preferably in this case about 18 feet above its lower end; the form of the 20 union being preferably such as shown at 32. The said rod 17 should be provided with a coupling 34 at its lower end and a coupling 35 at its upper end. These couplings should be nearly or quite as large in diameter as 25 the milling cutters, and in fact both the milling cutters and the couplings should be as large as possible and pass safely down through the well casing 10.

The drill bit 29 should not be larger 30 across its greatest width than the diameter of the coupling 34, as this coupling, cylindrical in external form, bears against the concave surface of the side-tracker 13, and serves as a journal or bearing in supporting the rotation of the rod 17. A similar 35 function is performed by the coupling 35 at the upper end of the rod where it rotates inside the well casing 10.

After an opening has been formed by the 40 tool 17' in the usual manner of side-tracking, the tool provided by the present invention may be lowered into the well, revolved and fed down in the usual way, whereupon its length and plurality of cutters will so 45 act upon the already formed opening through the well casing that it will be greatly increased in length and allow of more gradual change from the vertical within the well casing to the new position outside 50 thereof when the strainer is lowered into place. The opening is not only enlarged as described but the tool may be used in drilling the earth outside of the well casing by virtue of the bit 29 while the milling 55 cutters are acting upon the walls of the well casing. The combination of the drill bit 29 with the milling cutters is therefore of importance.

A desirable overall length of the tool, for 60 a six inch well, the usual size considered standard, is from 28 to 30 feet. When the tool has been operated and the opening completed therewith the opening will be such as to permit the passage through of a solid 65 bar of steel of the length mentioned, and as

large in diameter as the milling cutters, which will ensure that any shorter object, such as a strainer, will pass without any difficulty. The greatest amount of cutting will naturally be accomplished by the lowest cutter, certainly with the two lowest cutters.

Since these cutters have the greatest amount of work to do, the reduced diameter, at the lower end of the rod, provides for greater extension radially of their teeth, which is a 70 great advantage in taking a deep cut. The successive increases in diameter of the rod 17 will result in a considerable lightening thereof over what it would have been if the greatest diameter were carried to the lower 75 end. Since the tendency toward flexure is greatest at the center of the rod, the successive increases in diameter will result in the greatest strength being provided in the middle portion where it is needed, without 80 undue weight. In the event that the use of the tool 17' has resulted in a tendency to crookedness of the opening through the well casing the long straight rod provided by the invention will cure, and correct such defect 85 completely. With an opening provided by the tool of the present invention the strainer and liner placed in its new position, will depart from the vertical alignment of the well casing so gradually as to be practically imperceptible, so far as redrilling or operation of the well is concerned.

Minor changes may be made in the physical embodiment of the invention without departing from its spirit.

Having thus described my invention what I claim as new and desire to secure by Letters Patent is:

1. A well tool comprising a rod, a plurality of metal cutting milling cutters longitudinally spaced upon said rod.

2. A well tool comprising a rod, a plurality of internally threaded metal cutting milling cutters, longitudinally spaced upon said rod and attached thereto.

3. A well tool comprising a rod having successive offsets in its surface providing portions of different diameters, a metal cutting milling cutter at the lower end of each portion whereby to enlarge an opening in a well casing.

4. A well tool comprising a rod, having successive offsets in its surface providing portions of different diameters, a milling cutter threaded to the lower end of each portion whereby to enlarge an opening in a well casing.

5. A well tool comprising, in combination, a rod having a drill bit at its lower extremity and a plurality of longitudinally spaced metal cutting milling cutters above said bit.

6. A well tool comprising, in combination, a rod having a plurality of portions of different diameters decreasing as the lower ex-

tremity is approached, a milling cutter at the lower end of each portion, the radial extent of the milling teeth increasing upon the downwardly succeeding cutters.

5 7. A well tool comprising, in combination, a rod having a plurality of portions of different diameters decreasing toward the lower end of the tool, a metal cutting milling cutter at the lower end of each portion 10 and a drill bit at the lowest end of the tool.

8. A well tool comprising, in combination, a rod having a plurality of portions of different diameters decreasing as the lower extremity is approached, a hollow cylindrical 15 milling tool having cutting teeth upon its periphery and upon its end wall affixed to the lower end of each portion, the outer diameter of the cutters being substantially

equal whereby the radial extent of the cutting teeth upon the lower end of the milling 20 tools increases toward the lower end of the tool.

9. A well tool comprising, in combination, a rod having a plurality of portions of different diameters decreasing as the lower extremity is approached, a hollow cylindrical 25 milling tool having cutting teeth upon its periphery and upon its end wall affixed to the lower end of each portion, the outer diameter of the cutters being substantially 30 equal whereby the radial extent of the cutting teeth upon the lower end of the milling tools increases toward the lower end of the tool, a drill bit on the extremity of the smallest portion.

FRED I. GETTY.
